UNITED STATES PATENT OFFICE.

DANIEL MAGUSIAK, OF DETROIT, MICHIGAN.

ENGINE.

Application filed May 31, 1927. Serial No. 195,558.

This invention relates to an engine of the two cycle type, the general object of the invention being to provide means whereby a pure mixture is fed directly to the cylinders and does not pass through the crank case so that oil is not mixed with the fuel and said crank case can contain oil.

Another object of the invention is to provide a forced feed of the mixture from one cylinder into another and to provide a rapid intake of the mixture and to reduce to a minimum leakage of the mixture between the parts and also to reduce friction between the pistons and cylinder walls.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is an elevation of the improved engine, with parts in section.

Figure 2 is a longitudinal sectional view.

Figure 3 is a transverse sectional view.

Figure 4 is a section on line 4—4 of Figure 3.

Figure 5 is a transverse sectional view through one of the pistons.

In these views, 1 indicates the crank case upon which the cylinders 2 are supported, the cylinders being air cooled, though it will, of course, be understood that they may be formed with water jackets, if desired. Each

cylinder is formed with an enlarged lower portion which forms an annular compression chamber 3 and each piston 4 is provided with an enlargement 5 at its lower end which compresses the mixture in the

chamber 3 on the upward stroke of the piston. The pistons are arranged in pairs, as shown, with the pistons of each pair connected with oppositely arranged cranks of the crank shaft 6 by the connecting rods 7 so that as one piston of the pair is finishing its up stroke, the other piston is finishing its down stroke.

A casing 8 is arranged at one side of the engine and a pair of horizontally arranged partitions 9 divide the casing into three compartments, the lower compartment 10

forming the inlet manifold and is connected with the carburetor of the engine in the usual manner, a nipple 11 being formed on the lower part of the casing to receive the connecting pipe which leads to the carburetor or the carburetor may be fastened directly to this nipple. The second compartment is divided by the vertical partitions 12 into a plurality of chambers 13, one for each cylinder and an elongated port 14 connects each chamber 13 with the top part of each chamber 3 of the cylinder.

Vertically arranged Z-shaped partitions 15 divide the top compartment into a plurality of chambers 16, one for each cylinder and an elongated port 17 connects each chamber 16 with a cylinder adjacent the lower end of the small part of the cylinder, this port 17 being uncovered by the piston just before the piston reaches the end of its downward stroke. The lower partition has a plurality of ports 18 therein, one for each chamber 13, and these ports are normally held closed by the spring pressed valves 19. The upper partition 9 has a plurality of ports 20 therein for connecting each chamber 13 with a chamber 16, and as will be seen from Figure 4, port 20 at the rear end of the engine connects the chamber 13 at this end of the engine with the second chamber 16, while the port 20 of this second chamber 16 connects said chamber with the first chamber 13. One of the ports 20 connects the chamber 13 of the third cylinder with the chamber 16 of the fourth cylinder and the other port 20 connects the chamber 13 of the fourth cylinder with the chamber 16 of the third cylinder.

From the foregoing it will be seen that during the down stroke of each piston of each pair, a suction will be created in the chamber 3 by the enlarged part 5 of the piston so that the valve 19 will be lifted against the action of its spring and some of the mixture in the compartment 10 will be drawn into the chamber 13 of this cylinder and it will pass from this chamber through the port 14 into the space 3. Then on the upward stroke, this mixture in the space 3 will be forced therefrom back into the chamber 13, from which it will pass through the port 20 into the chamber 16 of the second cylinder of the pair and then as the piston of this second cylinder uncovers the port 17, the mixture will pass from the chamber 16 through the port 17 into the top part of the

cylinder where it will be compressed on the upward stroke of the piston. A baffle plate 21 is arranged on the top of each piston to direct the incoming mixture into the top part 5 of the cylinder and to prevent it from passing through the exhaust port 22 which is arranged in the opposite side of the cylinder from the inlet port 17. This incoming mixture will act to scavenge the exhaust gases 10 from the cylinder through the port 22 into the exhaust manifold 23. The mixture compressed in the top part of the cylinder by the piston is fired by the usual spark plug 24. The mixture forced into the chamber 15 13 of the second cylinder of the pair will pass through the port 20 into the chamber 16 of the first cylinder of the pair so that the piston of each cylinder of each pair will 20 act to deliver and pre-compress the mixture for the other cylinder of each pair.

The size of the chambers 13 and 16 should be made equal to the piston displacement volume so as to keep the mixture in a partly compressed state after it leaves the compression space 3. In this improved engine, 25 a pure mixture is fed directly to the cylinders as the mixture does not pass through the crank case so that it is not mixed with oil and oil can be used in the crank case and but a single crank case is used for an even 30 number of cylinders. Leakage is reduced to a minimum and the intake of the mixture is very rapid. The mixture entering the chamber 3 acts to cool the piston and there 35 is less friction between the piston and cylinder walls. There is also a forced feed of the mixture from one cylinder to another.

It is thought from the foregoing description that the advantages and novel features 40 of my invention will be readily apparent.

I desire it to be understood that I may make changes in the construction and in the combination and arrangement of the several parts, provided that such changes fall within 45 the scope of the appended claims.

What I claim is:—

1. A two cycle engine comprising a number of cylinders, a crank case connected with the cylinders, each cylinder having an enlarged inner end forming a compression 50

chamber, a piston in each chamber having an enlarged inner end operating in the compression chamber, a crank shaft in the crank case, a connecting rod connecting each piston with the crank shaft, each cylinder having inlet and exhaust ports therein which are uncovered when the piston is at the limit of its down stroke; an inlet manifold, a lower intake chamber for each cylinder in communication with the manifold, a spring pressed valve closing such communication; the cylinder having a port therein connecting each chamber with the compression chamber, and an upper intake chamber in communication with the inlet port of each cylinder and also in free communication with the lower intake chamber of a second cylinder. 55 60 65

2. A two cycle engine of the class described comprising a pair of cylinders, each provided with an enlarged inner portion forming a compression chamber, a piston in each cylinder having an enlarged lower end operating in the compression chamber, a casing arranged at one side of the cylinders, horizontal partitions in the chamber dividing the same into three compartments, means for connecting the lower compartment to a carburetor, vertical partitions in the central compartment dividing the same into lower intake chambers, the lower horizontal partition having ports therein connecting the chambers with the manifold, spring pressed valves normally closing said ports, each cylinder having a port therein for connecting each intake chamber with its compression chamber, vertically arranged Z-shaped partitions in the top compartment dividing the same into upper intake chambers and the upper horizontal partition having ports therein, each of which connects the upper 70 75 80 85 90 95 chamber of one cylinder with the lower chamber of the next cylinder, each cylinder having an inlet port leading to the upper intake chamber and an exhaust port, the inlet and exhaust ports being uncovered when the piston reaches the end of its downward stroke, a crank shaft and means for connecting the pistons thereto.

In testimony whereof I affix my signature.
DANIEL MAGUSIAK.
